UNITED STATES PATENT OFFICE.

MARIO LAVA, OF MILAN, ITALY.

VARIABLE RADIATOR.

Application filed January 3, 1925. Serial No. 407.

To all whom it may concern:

Be it known that I, MARIO LAVA, subject of the Kingdom of Italy, residing at Milan, Italy, have invented certain new and useful 5 Improvements in Variable Radiators, of which the following is a specification.

It is well known that radiators employed for cooling the engines of motor propelled vehicles do not function very satisfactorily 10 owing to the fact that they are subjected to large changes in temperature, due either to changes in the temperature of the surrounding medium, or to changes in speed, and this is particularly so in the case of 15 dirigibles and aeroplanes.

To overcome this objection it has been proposed to make the radiating capacity of radiators intended for these purposes, variable, so that it becomes possible to maintain 20 the circulating water at the most suitable temperature compatible with the maximum out-put of the motor.

It has also been proposed to arrange 25 valves controlled by thermostat devices in conduits within the radiator to regulate the proportion of the circulating water which passes through the radiator tubes, the remainder of the water being by-passed through the conduits. In these radiators 30 the side frame members of the radiator may form the conduits or the latter may be constituted by pipes or other hollow formations incorporated in the body of the radiator.

The accompanying drawing shows by way 35 of example one form of apparatus embodying the invention.

Fig. 1 thereof is a longitudinal sectional view.

Fig. 2 a transverse sectional view on 40 line 2-2, Fig. 1 looking in the direction of arrow E, and

Fig. 3 a side elevation.

As will be seen from Fig. 1, the radiator comprises a central body, divided into two 45 chambers by means of a diaphragm supporting a valve N controlled from the exterior by a member E.

The valve N may be of any suitable and 50 convenient form and in the drawing it is shown in the form of a rotary valve having an outer bell-shaped member X, fastened so as to make a water-tight joint with the wall Y of the central body, and a rotatably-mounted bell-shaped member C seating on 55 the inner surface of the member X. The rotatable member C is fastened to a shaft

F which passes to the outside of the radiator, through a water-tight gland G, where it is connected to a control lever H. A spring J serves to keep the rotatable member in contact with the inner surface of the member X. Both members X and C are provided with a number of holes D and D₁, respectively, so formed and disposed that, by a rotary movement of the inner member C, the two sets of holes may be brought completely into or out of register with one another or to any intermediate position.

The first chamber communicates with the second by way of a group of radiator tubes M in such a manner that when the valve N is closed the whole of the water circulating between P and O is obliged to pass through the tubes M and the water thereof is exposed over a large radiating surface.

If the surrounding temperature drops or if the travelling speed increases to that the radiating action becomes too great and the water is cooled to too great an extent, it is sufficient to gradually open the valve N to 80 remove a gradually increasing proportion of the circulating water from the cooling influence. It is possible to open the said valve to such an extent that the water flowing from O remains exactly at the desired temperature. If the valve is of a suitable size and is fully opened, the flow of water across the radiating tubes M may practically cease.

To ensure that the steam which may be generated inside the radiator can escape and 85 that the radiator may be emptied of the whole of its water content, the radiating tubes M are connected to a central tank Z provided with two valved unions the upper one Z₁ serving as an outlet for steam, and the lower one Z₂, as an outlet for water when the removal of the water becomes necessary.

The tank Z, which is of annular shape, encircles the tubes and is disposed in a plane normal to the same, said tubes passing 100 through holes in the tank Z, and being soldered thereto. The tubes M communicate with the tank Z by holes K.

It will be understood that many other constructions of radiator are possible without 105 departing from the scope of the present invention.

Having now particularly described and ascertained the nature of my said invention, and in what manner the same is to be performed, I declare that what I claim is:

1. A variable radiator, comprising a by-

pass; a valve in the by-pass dividing the interior thereof into two chambers; a group of cooling tubes providing communication between said chambers and with respect to which tubes the by-pass is centrally disposed; and means external to the radiator for operating said valve so as to control at will the quantity of circulation water which passes through said by-pass from one chamber directly to the other and thereby vary the quantity of water passing through said tubes.

5. A variable radiator, comprising a by-pass; a valve in the by-pass dividing the interior thereof into two chambers and embodying a perforated bell-shaped member fixed in the by-pass, and a perforated movable member associated therewith; a group of cooling tubes providing communication between said chambers and with respect to which tubes the by-pass is centrally disposed; a shaft mounted in the by-pass and to which the movable valve member is secured, said shaft projecting exteriorly of the by-pass at one end; and means connected to the exterior end of the shaft for rotating the movable valve member and bringing its perforations into or out of registration with those of the fixed member so as to control at will the quantity of circulation water which passes directly from one chamber to the other and thereby vary the quantity of water passing through said tubes.

6. A variable radiator, comprising a by-pass; a valve in the by-pass dividing the interior thereof into two chambers; a group of cooling tubes providing communication between said chambers and with respect to which tubes the by-pass is centrally disposed; means external to the radiator for operating said valve so as to control at will the quantity of circulation water which passes through said by-pass from one chamber directly to the other and thereby vary the quantity of water passing through said tubes.

7. A variable radiator, comprising a by-pass directly to the other and thereby vary the quantity of water passing through said tubes; and a tank with which all of the tubes communicate having separate outlets for discharging steam and water from the tubes.

8. A variable radiator, comprising a by-pass; a valve in the by-pass dividing the interior thereof into two chambers; a group of cooling tubes providing communication between said chambers and with respect to which tubes the by-pass is centrally disposed; means external to the radiator for operating said valve so as to control at will the quantity of circulation water which passes through said by-pass from one chamber directly to the other and thereby vary the quantity of water passing through said tubes; and an annular tank encircling the tubes and with which all of them communicate, said tank being disposed in a plane normal to the tubes and having separate outlets for discharging steam and water from the tubes.

9. A variable radiator, comprising a by-pass; a valve in the by-pass dividing the interior thereof into two chambers; a group of cooling tubes providing communication between said chambers and with respect to which tubes the by-pass is centrally disposed; means external to the radiator for operating said valve so as to control at will the quantity of circulation water which passes through said by-pass from one chamber directly to the other and thereby vary the amount of water passing through said tubes; and a tank external to the tubes and with which all of them communicate, said tank having separate outlets for discharging steam and water from the tubes, the steam outlet having a check valve.

In testimony whereof I affix my signature.
MARIO LAVA.
